UNITED STATES PATENT OFFICE.

EDWARD A. HENKLE, OF PHILADELPHIA, PENNSYLVANIA.

PRINTING-PRESS.

SPECIFICATION forming part of Letters Patent No. 634,819, dated October 10, 1899.

Application filed April 13, 1899. Serial No. 712,907. (No model.)

To all whom it may concern:

Be it known that I, EDWARD A. HENKLE, a citizen of the United States, residing at Philadelphia, in the county of Philadelphia and State of Pennsylvania, have invented 5 new and useful Improvements in Printing-Presses, of which the following is a specification.

In certain lines of printing it is frequently necessary to make partial changes of form—as, for example, in printing railway-tickets, transfers, labels, and the like, where the body of the form remains the same and the completed articles differ from each other only 15 in the matter of containing different dates, names of destination, &c. The ordinary method of making these changes is to incorporate the same in the body of the form where they are to appear and then to print 20 directly from the type, stopping the press, lifting the form, and changing the lines required, or to make as many separate plates of the whole form as there are to be changes and substitute one plate for another when a 25 change is required.

The object of my invention is to provide novel, effective, simple, and economical mechanism for accomplishing the purpose stated without stopping the press; and to this end my invention consists in the features of construction and the combination or arrangement of parts hereinafter described and claimed, reference being made to the accompanying drawings, in which—

Figure 1 is an end view illustrative of the relation between the impression-cylinder and the different printing-cylinders. Fig. 2 is an edge view of the impression-cylinder and one of the spindles operated thereby and containing a removable printing-sleeve. Fig. 3 is a 40 perspective view of one of the spindles with the detachable printing-cylinder removed. Fig. 4 is an end view of the same, the two parts being shown in locked position.

In carrying out my invention I employ an ordinary impression-cylinder 1, a roll 2 of the web of paper to be printed, a cutter 3, and a main or primary printing-cylinder designed 45 to carry the blank-spaced form and to cooperate with the impression-cylinder to print a

blank-spaced form—that is to say, a ticket, label, transfer, or like object—in such manner as to leave blank spaces thereon at certain predetermined points to be subsequently supplied with the required printed matter to 55 complete the same. The impression-cylinder 1 is provided with a gear-wheel 5, which meshes with a pinion 6 on a spindle 7 parallel with the shaft on which the impression-cylinder is mounted and located slightly beyond 60 the periphery of said cylinder. The spindle 7 is provided with a cylindrical head 8, having an annular shoulder 9 thereon adjacent to its inner end. The said head 8 is also provided with a groove 10, which is 65 adapted to be received by a feather or spline 11 in the printing-sleeve 12, having one or more plates 13 screwed or otherwise secured to its outer surface and containing the matter to be printed in the blank spaces left in 70 the ticket or other form. The said sleeve 12 fits snugly upon the head 8 of the spindle and is locked in place thereon by means of a washer 14, which fits over the extended 75 threaded end of the spindle 7 and engages the outer edge of said sleeve. The washer 14 is itself held in place by means of a split washer 15, which also embraces the end of said spindle and is forced inwardly and locked by means of nut 16.

In the foregoing description I have referred to but one spindle 7 and the parts co-operating therewith to provide the secondary printing mechanism, which prints in the aforesaid blank spaces in the form printed by the main 85 or primary printing cylinder or mechanism. It will be obvious, however, that I may use a plurality of said spindles containing printing cylinders or sleeves having different matter thereon for the purpose of printing in the different blank spaces left in the ticket, label, or the like by the blank-spaced form of the main or primary printing cylinder or mechanism.

Suitable inking devices will of course be 95 provided for the printing cylinders or mechanisms; but it is not considered necessary to describe the same.

Constructed as above described it will be observed that if it be desired at any time to 100

change the matter which is to be printed in the blank spaces on the form all that it is necessary to do is to loosen the nut 16 on the end of the spindle 7, remove the split washer 5 15 and the main washer 14, and then slip the sleeve 12 from its seat on the head 8. To apply another cylinder containing different form-matter—as, for example, the date of the transfer or other ticket or the destination to 10 which the ticket is to be issued—it is simply necessary to place a new sleeve 12 on the head 8 so that the spline or feather 11 will fit within the spline way or groove 10, insert the washer 14 over the end of the nut 16, apply the split 15 washer 15, and tighten said nut 16. When applied in this manner, the sleeve is held securely in place on the spindle, its proper registration with the blank spaces in the form printed by the cylinder 4 being obtained by 20 locating the feather or spline 11 in the printing-sleeve 12 at such position that when it is engaged by the groove 10 the spaced-apart forms or printing-plates 13 on the sleeve 12 will come directly opposite the blank spaces 25 in the main form.

It will be understood that the idea of my invention is to avoid the delay incident to changing the plates on an ordinary rotary printing-machine for each change of form, 30 the lost time being that which is necessary to screw or clamp the plate in position on its cylinder and to adjust the same for register after it is on. It is frequently necessary to build up low and defective plates, and this is 35 usually accomplished by pasting overlays on the impression-cylinder, which overlays of course are not only useless on the next change of form, but require scraping off and renewing to suit the next change. I paste them to 40 the back of the plate before it is screwed onto its sleeve, thus insuring its permanency and obtaining a material saving in the operation of making ready the form, as the underlay being between the plate and sleeve cannot be 45 displaced. This is material and important and is a great time-saving factor in changes of small editions, which require a complete stoppage of an expensive machine for a very considerable part of the time and very materially reduces the production. I propose to 50 have in stock a quantity of printing cylinders or sleeves which have plates thereon containing different form-matter to be printed in the blank spaces in the main form already "made-ready" and imposed to register without adjustment, and when it is desired to change all 55 that is necessary to be done is to substitute one sleeve for another, the removal of the old sleeve and the application of the new one being effected in the manner heretofore set forth.

It will be seen that in the construction and combination described for first printing a 60 form with blank spaces and subsequently printing any desired matter in said blank spaces the provision of the cylindrical heads

and sleeves with interlocking grooves and splines or feathers arranged in the manner set forth is advantageous, desirable, and important in that by merely slipping the sleeves 70 on the cylindrical heads and causing the grooves and splines or feathers to interlock the sleeves are not only forced to turn with the cylindrical heads, but the grooves and splines or feathers constitute registering devices whereby the spaced-apart printing-forms 75 on the sleeves without further attention or manipulation are caused to accurately register with the blank spaces of the form on the main or primary printing-cylinder, as herein-before explained. Although I have described and shown the spline or feather in the sleeve and the groove on the cylindrical head, they may be reversed without altering the function 80 of these parts. 85

Having now described my invention, what I claim as new, and desire to secure by Letters Patent, is—

1. In a printing-press, the combination with an impression-cylinder, and a main printing-cylinder designed to print a form containing blank spaces to be subsequently supplied with printed matter, of a spindle having a cylindrical head provided with a register-groove, a cylindrical printing-sleeve detachably mounted on said head and provided interiorly with a register-spline and exteriorly with a spaced-apart printing-plate for printing in the aforesaid blank spaces, the groove and spline being arranged to cause registration of the 100 spaced-apart printing-plates on the sleeve with the said blank spaces of the main printing-cylinder as the sleeve is placed upon the cylindrical head, substantially as described. 95

2. In a printing-press, the combination with an impression-cylinder, and a main printing-cylinder designed to print a form containing blank spaces, of a spindle having a cylindrical head geared with the impression-cylinder and constructed with a register-groove, 110 a cylindrical printing-sleeve lengthwise removable from the cylindrical head and provided interiorly with a register-spline and exteriorly with spaced-apart printing-plates to register with the aforesaid blank spaces to 115 print the required matter therein, said groove and spline interlocking and arranged to cause registration of the said spaced-apart printing-plates with said blank spaces and devices for detachably holding the printing-sleeve on the 120 cylindrical head, substantially as described.

3. In a printing-press, the combination with an impression-cylinder, and a main printing-cylinder designed to print a form containing blank spaces to be subsequently printed in, 125 of a head having a pinion and a register-groove and a central screw-threaded projection at one end, a cylindrical printing-sleeve lengthwise removable from the head and having an interior spline and exterior spaced-apart printing-plates registering with the aforesaid blank spaces, a washer arranged on 130

the screw-threaded extension and overlapping one end portion of said sleeve, and a nut for holding the washer in place, the interlocking groove and spline being arranged to register 5 the spaced-apart printing of the sleeve-plates with the blank spaces of the main printing-cylinder, substantially as described.

In testimony whereof I have hereunto set my hand in presence of two subscribing witnesses.

EDWARD A. HENKLE.
